UNITED STATES PATENT OFFICE

2,029,634

PNEUMATIC DRIVE SYSTEM

Charles Peter, West Allis, Wis., assignor to Allis-Chalmers Manufacturing Company, Milwaukee, Wis., a corporation of Delaware

Application October 10, 1932, Serial No. 637,025

3 Claims. (Cl. 121—40)

This invention relates to improvements in servo-motors and servo-motor controlled systems and more particularly to fluid pressure operated servo-motors when used in connection with electrical control apparatus.

Servo-motors operated by fluid pressure are employed in many ways to secure control or operation of apparatus or mechanisms particularly when such apparatus is located at points remote from the point in which the operator is located. Such servo-motors are usually provided with pistons acting in both directions to secure forward or reverse operation of the apparatus which such motors serve. Such double acting servo-motors, however, heretofore required duplicate pressure lines and control valves and greatly complicated the control equipment and the control operations for the apparatus. Such duplication not only increases the expense but also increases the possibilities of failure of equipment, thus preventing the design of rugged and absolutely trustworthy systems.

It is, therefore, among the objects of the present invention to provide a fluid pressure operated servo-motor which will require only a single connection with the fluid pressure source and which is provided with a single valve to control both the supply to and the discharge of fluid from the servo-motor.

Another object of the invention is to provide a single piston fluid pressure operated servo-motor to operate a control system requiring reversal of operation of the apparatus to be controlled.

Another object of the invention is to provide a single piston fluid pressure operated servo-motor to operate a control system requiring reversal of operation of the apparatus to be controlled in which the conditions for reversal are fulfilled and such reversal takes place prior to the occurrence of the need therefor.

Objects and advantages other than those above described will be apparent from the following description when read in connection with the accompanying drawing, in which:

Fig. 1 diagrammatically represents one embodiment of a servo-motor illustrating the present invention as applied to control apparatus of individually electrically driven railway cars to be controlled from a remote point on a train composed of such cars;

Fig. 2 is a vertical cross sectional view of the servo-motor taken on the plane II—II of Fig. 3 and illustrating the manner of engagement of the main piston of the servo-motor with one of the

control drums of a multiple unit train for operation of the traction motor on the particular car on which the servo-motor is located;

Fig. 3 is a vertical longitudinal section of the main piston of the servo-motor taken on the plane III—III of Fig. 2 and illustrating in detail the operating connection between the main piston and one of the control drums of a multiple unit car; and

Fig. 4 is a vertical longitudinal sectional view of the auxiliary piston of the servo-motor taken on the plane IV—IV of Fig. 2 to illustrate the manner in which the control drum, operated by the main piston of the servo-motor, is retained in the presently attained position upon return of the main piston to its starting position in preparation for another operating stroke thereof.

Referring more particularly to the drawing by characters of reference, the reference numeral 11 designates a supply line which may be either an overhead trolley line or a third rail as desired. Current is drawn from the line 11 by current collecting means 12 such as a pantograph or a third rail shoe and is supplied to traction motors 13 through a main switch 14 and a reversing switch 15 or controller 16 which reverses the connection of the motor with the current collector from forward to reversing positions or vice versa as will be set forth hereinafter. Reverser 16 is operated by a servo-motor, to be specifically described herein-after, operated by fluid pressure from a suitable source (not shown) under the control of a magnet valve 17. The coil of valve 17 is connected to be energized from a source of current 18 and opens the connection with the fluid pressure source against the action of a spring upon cooperative action of a selector switch 19 associated with the reverser 16 and a main controller 20, of which only one contact or switch portion is shown, located on the car to be controlled. The main controller 20 is in turn controlled by a master controller 21 and the entire control operation takes place as will be described. Reference numeral 22 designates a socket through which the servo-motors of other cars may be connected with battery 18 and through which the main controller 20 of such other cars may be controlled by a single master controller 21.

The servo-motor is formed with a main piston 31 and an auxiliary piston 32 which are preferably arranged in side-by-side relation in a common block or casing 33 although shown diagrammatically, for the purposes of clearness, in Fig. 1 as being arranged in separate blocks. The cylinders within which the pistons are arranged are

connected to receive fluid under pressure from the same source (not shown) through valve 17. The pistons are associated with springs 36 and 37 respectively which are arranged within the cylinders and tend to return the pistons to the neutral position against the pressure of the fluid from the fluid pressure source.

A slot is formed in one side of piston 31 and receives a pin 38 extending thereinto to permit longitudinal movement of the piston but prevent rotating movement thereof. A stud 39 with a transverse pin 41 is attached to piston 31 and extends upward therefrom through a slot in the cylinder containing the piston 31 and engages with a forked double plate 42 which is rotatably mounted on the shaft 43 of the reverser-selector drum 16, 19, one end of the shaft being supported in a bearing 44 formed integral with the servo-motor block. The plate 42 carries a pawl 46 held under the pressure of spring 47 and arranged to engage with a ratchet wheel 48 keyed on shaft 43 and having four teeth. Reverser-selector 16, 19 is thus rotated one-quarter revolution, by ratchet 48 and pawl 46, for each stroke of the piston 31 by engagement of pin 41 with plate 42 and the consequent engagement of pawl 46 with wheel 48.

The auxiliary piston is provided with a recess into which a latch 51 extends, such latch being pivotally mounted on the block 33. The latch is arranged to engage a latch wheel 52 which is keyed to the shaft 43 and is provided with four notches corresponding in position with the positions of the teeth of the ratchet 48. Thus when piston 31 rotates drum 16, 19 by one-quarter revolution, piston 32 is likewise operated thereby withdrawing latch 51 from engagement with latch wheel 52.

In operation, when the several portions of the system are in the position shown, master controller 21 is in the zero position and main controller 20 is likewise in the zero position. Reverser 16 is then in position to connect the field and the armature of the motors 13 in series for reverse operation of the car. Selector 19 is in such position that the circuit to valve 17 is interrupted and the spring connected with such valve has, therefore, connected the cylinders containing pistons 31 and 32 with the discharge port from the valve. Movement of master controller 21 into the first forward operation position completes a circuit from the battery 18 with the coil of the valve 17 excepting that the main controller 20 is still in the neutral position. Upon movement of controller 20 into an operating position, the coil of valve 17 is energized and the position of the valve is changed to permit connection of the cylinders containing the pistons 31 and 32 with the source of fluid pressure. Both pistons of the servo-motor then receive fluid under pressure. Main piston 31 moves plate 42 and pawl 46 to the end of its stroke, thus causing movement of the drum 16, 19 to the next following position. Movement of the master and main controllers into an operating position interrupts the circuit to the coil of valve 17 and the valve is reversed under the action of the spring to permit the cylinders to discharge under the actions of the spring and to thus cause preparation for a new movement. Continued movement of main controller 21 through the operating positions is followed by movement of main controller 20 through its operating positions until the neutral positions of both the master controller and the main controller are again reached. When the

master controller and the main controller 20 and 21 respectively are again in the neutral position, motor 13 being still connected for further forward operation of the car, and the circuit to valve 17 being open, movement of master controller 21 into position for reverse operation closes the circuit from battery 18 over main controller 20 to the coil of valve 17 which again admits fluid under pressure to the servo-motor thus causing reversal of the connection of the motor 13 and interruption of the circuit to the coil of valve 17 as described above. After such operation of the servo-motor, the connections of the motor 13 having been changed and the connection between battery 18 and coil of valve 17 having been interrupted, movement of master controller 21 through the reversing positions and the resulting movement of main controller 20 through the reversing positions permits reverse movement of the car.

At each movement of the drum 16, 19 which 20 reverses the connection of the motor 13 and interrupts the circuit from battery 18 to the coil of valve 17, the spring connected with the valve 17 reverses the position of the valve which opens the connection with the cylinders containing the 25 pistons 31 and 32 and the springs 36 and 37 return the pistons to their previous position. Latch 51 then reengages wheel 52 and retains drum 16, 19 in the presently attained position. The connections to the motors 13 having been reversed, a 30 circuit to the valve is prepared to repeat operation of the servo-motor as above described, such circuit being completed upon movement of master controller 21 into the first position and before movement of main controller into such first po- 35 sition. It will thus be seen that the present system provides means whereby the connections of the motor are prepared for reversal of operation only after such operation has been initiated at the master controller and before current has been 40 applied to the motor 13 by the main controller. Consideration of the particular construction of the servo-motor involved shows that it is impossible for vibration to disturb the positive operation of the servo-motor and that the valve con- 45 trolling the flow of fluid pressure to the servo-motor and the discharge therefrom is interlocked with both the main and the master controllers to avoid operation thereof excepting in the sequence above set forth.

Although but one embodiment of the present invention has been illustrated and described, it will be apparent to those skilled in the art that various changes and modifications may be made therein without departing from the spirit of the 55 invention or from the scope of the appended claims.

It is claimed and desired to secure by Letters Patent:

1. In a fluid pressure operated system, a shaft 60 to be rotated, a fluid pressure operated motor and a single valve controlling the flow of fluid under pressure to said motor, said motor comprising a main piston for stepwise rotation of said shaft in the same direction, a ratchet mounted on said shaft to drive the same, a pawl arranged for operation by the main piston for engagement with the ratchet, an auxiliary piston, said main and said auxiliary pistons moving along parallel axes, a latch wheel mounted on said shaft, and a latch 65 arranged for movement by the auxiliary piston and for engagement with the latch wheel to retain said shaft in position.

2. In a fluid pressure operated system, a shaft 70 to be rotated, a fluid pressure operated motor and 75

5 a single valve controlling the flow of fluid under pressure to said motor, said motor comprising a main piston for driving said shaft step by step in the same direction, a ratchet mounted on said shaft to drive the same, a pawl arranged for operation by the main piston for engagement with the ratchet, an auxiliary piston, a latch wheel mounted on said shaft, and a latch arranged for movement by the auxiliary piston, and a plurality 10 of springs for severally returning the pistons to inoperative positions.

10 3. In a fluid pressure operated system, a shaft to be rotated, a single fluid pressure operated motor and a single valve controlling the flow of fluid

under pressure to said motor, said motor comprising a main piston, and an auxiliary piston, said main and said auxiliary pistons being operable alternately in the same direction along parallel axes, a ratchet wheel mounted on said shaft to 5 drive the same, a pawl arranged for operation by the main piston for engagement with the ratchet wheel, a latch wheel mounted on said shaft, and a latch arranged for movement by the auxiliary piston and for engagement with the latch wheel 10 to retain said shaft in position between driving operations of the main piston.

CHARLES PETER.
